Term of patent 3½ years

To all whom it may concern:

Be it known that I, Frederick M. Robert Burns, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of my design resides in the combination on the dress as shown of the drawn work scallops on the front opening, and on the cuffs of the simulated bolero member.

I claim:

The present application is a substitute for my prior application filed March 3, 1936, Serial No. D-61,454.

The ornamental design for a dress, substantially as shown and described.
